The ornamental design for a scarf, as shown and described.

DESCRIPTION

FIG. 1 is a front view of the scarf that has a slit in the center thereof showing my new design;
FIG. 2 is a back view thereof;

FIG. 3 is a top-plan view thereof, the bottom view being a mirror image of FIG. 3;

FIG. 4 is a right side view thereof;

FIG. 5 is a left view thereof;

FIG. 6 is a reference view thereof showing the scarf in use;

FIG. 7 is an enlarged perspective view thereof showing the slit in an alternate open position;

FIG. 8 is a cross sectional view thereof cut along the line 8-8 in FIG. 1;

FIG. 9 is another front view thereof, in which ornamental marks are illustrated with broken-lines; and,

FIG. 10 is an enlarged view thereof cut along the circle 10 in FIG. 8.

The broken line showing is for the purpose of illustrating environmental structure and forms no part of the claimed the design.
